BY

Robert A. Solomon

ATTORNEY.

tion 28 now withdraws completely from retainer die 13 with this movement being preceded by a forceful movement to the left of knockout shaft 27 as well as a resulting knockout movement of holder 16 and die 19 to the left. Thus the formed punched nut 29, shown in Fig. 4, is ejected ahead of the withdrawing of the punch, there being a suitable stripper D whereby the nut is stopped after leaving retainer die 19 and permitted to drop away from the path of movement of punch B.

It will be understood that reciprocable motion of punch B is continuous with single nut blanks 12 being successively presented in front of opening 14 in retainer 19 and in the path of moving punch B.

There is a tendency for the pellet 22 to follow the withdrawing punch B; and to prevent this, opening 24 is offset from opening 23 within piercing die 19 providing annular shoulder 30.

Cylindrical pellet holder pin 31 with flanged head 32 is transversely and reciprocably provisioned through corresponding openings in piercing die 19 and its holder 16.

Piston 33 transversely and reciprocably provisioned within sleeve 15 operatively engages head 32 of pin 31, being adapted to intermittently project said pin into opening 24 of piercing die 19.

Movement inwardly of pin 31 is timed to coincide with the positioning of pellet 22 within opening 24 as shown in dotted lines in Fig. 6, so that the inner end of said pin operatively engages the edge of said pellet projecting the same upwardly. Thus any tendency of pellet 22 to return on withdrawing movement of punch B is prevented by the engagement of said pellet with the annular shoulder 30 formed within piercing die 19.

As shown in Fig. 1 a suitable bell crank 34 pivoted at 35 is adapted to intermittent reciprocable pivotal movement effecting upward movement of push rod 36 joined thereto at 37. Said push rod with central collar 38 movably projects through a suitably supported bracket 39 with its upper end operatively engaging pellet pin actuating cylinder 33.

Coiled spring 40 interposed between collar 38 and bracket 39 resiliently maintains push rod 36 in a slightly elevated position when bell crank 34 is in inoperative position, whereby the inner end of pin 31 projects partially within opening 24 in piercing die 19.

The pivotal movement of said bell crank is timed to coincide with the end of the inward punching movement of punch B so that the inner operative end of pin 31 engages the pellet as it reaches the dotted line position shown in Fig. 6. It will be understood that the relative positioning of pin 31 on the punched pellet is attained by the prompt return of piercing die 19 to the left as soon as said pellet is punched out. In other words, in the manner hereafter described, piercing die 19 moves to the left even before punch 13 has completed its punching stroke, whereby said pellet is transferred relatively from opening 23 to opening 24 in piercing die 19.

Knockout shaft 27 is reciprocably provisioned horizontally through bushing 41 within nut forming machine bed 11 adjacent one end thereof, with its other end slidably projecting through bushing 42 and outwardly beyond the end of said forming machine bed.

Inward movement to the right of piercing die holder 16 effected by action of punch B results in movement to the right of knockout shaft 27. However resilient means are employed for effectively and promptly causing a snap ejecting move-

ment to the left of said shaft preceding the withdrawal movement of punch B. Thus by the ejecting action of knockout shaft, holder 16 is returned to its initial position and the punched nut is forcefully projected outwardly to the left from retainer die 13 for proper disposal.

As shown in Fig. 2 trunnion carrying ring 43 is transversely carried on knockout shaft 27 by means of its supporting nut 44 which threadably engages the outer threaded end 45 of said shaft. A suitable lock nut 46 is threaded upon the end of shaft 27 for retaining ring supporting nut 44 in any desired adjusted position relation to said shaft.

Oppositely provisioned trunnions 47 and 48 on trunnion carrying ring 43 project through corresponding openings in the two parallel spaced levers 49 and 50 shown in Fig. 2.

Said levers are pivotally carried at their upper ends by transverse bolt 51 provisioned through corresponding openings in the spaced horizontal outwardly projecting links 52 and 53 suitably bolted and secured to the forming machine bed by bolt 54. Longitudinal movement to the right of shaft 27 thus effects an outward pivotal movement of levers 49 and 50 around bolt 51.

Transverse cross bar 55 suitably secured at 56 and 57 to the lower ends of levers 49 and 50 carries a plurality of hollow bushings 58 shown in Fig. 1, adapted to slidably and reciprocably engage the three parallel stationary shafts 59, 60 and 61 suitably secured at 62 at their inner ends to the forming machine bed 11.

Nuts 62, 63 and 64 are respectively threaded upon the outer ends of shafts 59, 60 and 61 for retaining the annularly flanged spring stops 65, 66 and 67. Coiled springs 68 are provisioned over substantially the length of shafts 59, 60 and 61 respectively interposed between annular flanges 69 on slidable bushings 58 and the annular flanges 70 on the stationary spring stops 65, 66 and 67.

This construction thus permits a very substantial compression of said coiled springs upon the outward pivotal movement of levers 49 and 50 which operatively join knockout shaft 27. The potential energy stored in springs 68 is sufficient to effectively and forcefully actuate levers 49 and 50 to the left as soon as knockout shaft 27 is released after the punching operation and prior to punch B returning to its inoperative position.

Knockout shaft 27 is then projected to the left forcefully actuating die holder 16 which in turn through piercing die 19 forcefully ejects the punched nut 29 from its retaining die 13.

It will be noted that a suitable shock absorbing anvil 71 is interposed between trunnion carrying ring 43 and the shaft bushing 42 for minimizing the shock effected by resilient returned levers 49 and 50 following each punching operation.

In operation it is seen that knockout shaft 27 is projected to the right by action of punch B operatively engaging the nut blank, and inserting it within retainer die 13, so that it operatively engages the outer end of piercing die 19 effecting forceful movement thereof to the right. Holder 16, which carries said piercing die, likewise moves to the right until it engages anvil 71; therefore knockout shaft 27, which is in engagement with holder 16, is also projected to the right compressing coiled springs 68.

Thus it is the central portion 22 of the nut blank which maintains knockout shaft 27 in its extreme position to the right. As soon as punch B separates the nut blank from its central por-

tion said knockout shaft is released, promptly returning to the left for ejecting the punched nut.

Thus it is seen that the piercing die as well as its holder is automatically returned to its initial inoperative position even before the punch has completed its forward stroke.

Having described my invention reference should now be had to the claims which follow for determining the scope thereof.

I claim:

1. A nut punching attachment for a nut forming machine comprising a hollow retainer, a hollow reciprocable means therein, a hollow piercing die carried by said means, a hollow nut retainer die in said retainer consisting of a ring with a polylateral slot to supportingly retain the sides of a nut blank, and a reciprocable punch for inserting a nut blank into said retainer die and for removing the central portion thereof.

2. A nut punching attachment for a nut forming machine comprising a hollow retainer, a hollow reciprocable means therein, a hollow piercing die carried by said means, a hollow nut retainer die in said retainer consisting of a ring with a polylateral slot to supportingly retain the sides of a nut blank, a reciprocable punch for inserting a nut blank into said retainer die and for removing the central portion thereof, the inner surfaces of said retainer die corresponding to the outer surfaces of said nut blank to prevent distortion thereof during the punching operation.

3. A nut punching and ejecting attachment for a nut forming machine comprising a hollow retainer, a hollow reciprocable means therein, a hollow piercing die carried by said means, a hollow nut retainer die in said retainer consisting of a ring with a polylateral slot to supportingly retain the sides of a nut blank, a reciprocable punch for inserting a nut blank into said retainer die and for removing the central portion thereof, and means for ejecting the punched nut from said retainer die.

4. A nut punching and ejecting attachment for a nut forming machine comprising a hollow retainer, a hollow reciprocable means therein, a hollow piercing die carried by said means, a hollow nut retainer die in said retainer consisting of a ring with a polylateral slot to supportingly retain the sides of a nut blank, a reciprocable punch for inserting a nut blank into said retainer die and for removing the central portion thereof, expandible resilient means, compressed during the punching operation, for ejecting the punched nut from said retainer die.

5. A nut punching mechanism comprising a hollow retainer, a hollow nut blank retainer die in the end thereof consisting of a ring with a polylateral slot to supportingly retain the sides of a nut blank, a hollow reciprocable means in said retainer, a hollow piercing die carried by said means and adapted for movement into said retainer die, and a reciprocable punch for initially projecting a nut blank into said retainer die and into operative engagement with said piercing die, and also for removing the central portion of said blank upon further movement relative to said piercing die.

6. A nut punching and ejecting mechanism comprising a hollow retainer, a hollow nut blank retainer die in the end thereof consisting of a ring with a polylateral slot to supportingly retain the sides of a nut blank, a hollow reciprocable means in said retainer, a hollow piercing die carried by said means and adapted for movement

into said retainer die, a reciprocable punch for initially projecting a nut blank into said retainer die and into operative engagement with said piercing die and also for removing the central portion of said blank upon further movement relative to said piercing die, and expansible resilient means, compressed on initial movement of said piercing die, for ejecting the punched nut from said retainer die after the punching operation.

7. A nut punching mechanism comprising a hollow retainer, a hollow retainer die in the end thereof consisting of a ring with a polylateral slot for slidably and snugly receiving a nut blank, a hollow reciprocable means in said retainer, a hollow piercing die carried by said means, a reciprocable punch for initially projecting a nut blank into said retainer die and into operative engagement with said piercing die, and also for removing the central portion of said blank upon further movement relative to said piercing die, and keeper means projecting into said piercing die for retaining said punched portion on reciprocal movement of said punch.

8. A nut punching mechanism comprising a hollow retainer, a hollow retainer die in the end thereof consisting of a ring with a polylateral slot for slidably and snugly receiving a nut blank, a hollow reciprocable means in said retainer, a hollow piercing die carried by said means, a reciprocable punch for initially projecting a nut blank into said retainer die and into operative engagement with said piercing die, and also for removing the central portion of said blank upon further movement relative to said piercing die, transverse resiliently mounted keeper means provisioned through said reciprocable means and projecting into the interior of said piercing die for operative retaining engagement with said punched out portion, and a reciprocable cylinder slidably provisioned through said hollow retainer for operative engagement with said keeper means.

9. A nut punching mechanism comprising a hollow retainer, a hollow retainer die in the end thereof consisting of a ring with a polylateral slot for slidably and snugly receiving a nut blank, a hollow reciprocable means in said retainer, a hollow piercing die carried by said means, a reciprocable punch for initially projecting a nut blank into said retainer die and into operative engagement with said piercing die, and also for removing the central portion of said blank upon further movement relative to said piercing die, transverse resiliently mounted keeper means provisioned through said reciprocable means and projecting into the interior of said piercing die for operative retainer engagement with said punched out portion, a reciprocable cylinder slidably provisioned through said hollow retainer for operative engagement with said keeper means, and reciprocable rotary means operatively engageable with the outer end of said cylinder in timed relation to movements of said punch.

10. A nut punching mechanism comprising a hollow retainer, a hollow retainer die in the end thereof consisting of a ring with a polylateral slot for slidably and snugly receiving a nut blank, a hollow reciprocable means in said retainer, a hollow piercing die carried by said means and having an annular shoulder therein, a reciprocable punch for initially projecting a nut blank into said retainer die and into operative engagement with said piercing die, and also for removing the central

portion of said blank upon further movement relative to said piercing die, and keeper means projecting into said piercing die for elevating said punched portion into retaining engagement with said annular shoulder.

11. A nut punching and ejecting mechanism comprising a hollow retainer, a hollow reciprocable means therein, a hollow piercing die carried by said means, a hollow nut retainer die in said retainer consisting of a ring with a poly-lateral slot to supportingly retain the sides of a nut blank, a reciprocable punch for inserting a nut blank into said retainer die and for removing the central portion thereof, and a reciprocable knockout shaft operatively engaged by said reciprocable means, and adapted to operatively engage said means in the opposite direction for ejecting the punched nut from said retainer die.

12. A nut punching and ejecting mechanism comprising a hollow retainer, a hollow reciprocable means therein, a hollow piercing die carried by said means, a hollow nut retainer die in said retainer consisting of a ring with a poly-lateral slot to supportingly retain the sides of a nut blank, a reciprocable punch for inserting a nut blank into said retainer die and for removing the central portion thereof, a reciprocable knockout shaft operatively engaged by said reciprocable means, and adapted to operatively engage said means in the opposite direction for ejecting the punched nut from said retainer die, and expansible resilient means compressed on initial movement of said shaft.

13. A nut punching and ejecting mechanism comprising a hollow retainer, a hollow reciprocable means therein, a hollow piercing die carried by said means, a hollow nut retainer die in said retainer consisting of a ring with a poly-lateral slot to supportingly retain the sides of a nut blank, a reciprocable punch for inserting a nut blank into said retainer die and for removing the central portion thereof, a reciprocable knockout shaft operatively engaged by said reciprocable means, and adapted to operatively engage said means in the opposite direction for ejecting the punched nut from said retainer die, pivoted lever means joined to said shaft, and expansible resilient means joined to said lever means, compressed on initial movement of said shaft.

14. A nut punching and ejecting mechanism comprising a hollow retainer, a hollow reciprocable means therein, a hollow piercing die car-

ried by said means, a hollow nut retainer die in said retainer consisting of a ring with a poly-lateral slot to supportingly retain the sides of a nut blank, a reciprocable punch for inserting a nut blank into said retainer die and for removing the central portion thereof, a reciprocable knockout shaft operatively engaged by said reciprocable means, and adapted to operatively engage said means in the opposite direction for ejecting the punched nut from said retainer die, pivoted lever means in spaced relation, trunnion means carried by said shaft intermediately and pivotally joining said lever means, and expansible resilient means joined to said lever means, compressed on initial movement of said shaft.

15. A nut punching and ejecting attachment for a nut forming machine comprising a hollow retainer, a hollow reciprocable means therein, a hollow piercing die carried by said means, a hollow nut retainer die in said retainer, a reciprocable punch for inserting a nut blank into said retainer die and for removing the central portion thereof, a reciprocable knockout shaft operatively engaged by said reciprocable means, and adapted to operatively engage said means in the opposite direction for ejecting the punched nut from said retainer die, spaced lever means pivotally supported by said forming machine, trunnion means carried by said shaft intermediately and pivotally joining said lever means, and expansible resilient means joined to said lever means, compressed on initial movement of said shaft.

16. A nut punching and ejecting attachment for a nut forming machine comprising a hollow retainer, a hollow reciprocable means therein, a hollow piercing die carried by said means, a hollow nut retainer die in said retainer, a reciprocable punch for inserting a nut blank into said retainer die and for removing the central portion thereof, a reciprocable knockout shaft operatively engaged by said reciprocable means, and adapted to operatively engage said means in the opposite direction for ejecting the punched nut from said retainer die, spaced lever means pivotally supported at one end by said forming machine, trunnion means carried by said shaft intermediately and pivotally joining said lever means, and expansible resilient means joined to the other end of said lever means, compressed on initial movement of said shaft.

PAUL DE LOE.
